SIDNEY SMITH, OF WORCESTER, MASSACHUSETTS.

Letters Patent No. 79,020, dated June 16, 1868.

IMPROVEMENT IN HOT-AIR FURNACES.

The Schedule referred to in these Letters Patent and making part of the same.

TO ALL WHOM IT MAY CONCERN:

Be it known that I, SIDNEY SMITH, of Worcester, in the county of Worcester, and State of Massachusetts, have invented a new and useful Improvement in Furnaces; and I do hereby declare the following to be a full, clear, and exact description of the same, reference being had to the accompanying drawings, in which—

Figure 1 is a perspective view of my furnace, with a portion of the side wall removed to exhibit the construction.

Figure 2 is a vertical cross-section of the same.

Figure 3 is a vertical longitudinal section through the centre of the same.

Figure 4 is a plan, with the cover of the hot chamber removed.

My furnace belongs to that class which converts fuel into heat for the purpose of warming and ventilating buildings; and my invention consists, first, in the use of a number of deflecting-plates, to bring the moving currents of air in contact with the radiating surface of the furnace; second, in forming the said radiating surface with a series of corrugations transverse to the direction of the moving currents of air; and, third, in the manner of arranging the air-chamber or reservoir at the top of the furnace, and introducing the hot-air pipes thereto.

As heating-furnaces of the class above mentioned are usually constructed, there is a surrounding space within the outer casing or jacket, more or less large, within which the air may circulate and be exposed to the action of the heat radiated from the walls of the fire-chamber. Atmospheric air is a slow conductor of heat, and from experience it has been found that when the registers at the ends of the hot-air ducts are opened, a rapid current of air may be induced through the hot-air chamber surrounding the furnace, and that this current will sometimes pass through said chamber so rapidly as to make its exit therefrom almost at the same temperature as when it entered; consequently it is frequently impossible to warm more than a portion of the house at one time. It is also observed that air which has been heated by its passage through the hot-air chamber of such a furnace, has been deprived of its moisture, and it is necessary to supply this again by artificial means, or, if not so supplied, the air is immediately noticeable as hot, dry, and oppressive.

These disadvantages are remedied in my apparatus, first, by preventing the passage of any volume of air through the hot chamber without being brought into close contact with the radiating surface; second, by producing a thorough intercirculation and equalization of the temperature of the enclosed air; third, by causing the moving currents of air to pass in close contact with the radiating surface so rapidly that it will not be heated to a degree sufficient to deprive it of its moisture; fourth, by heating a large volume of air moderately, rather than heating a small volume to a high degree. In furnaces as usually constructed, the currents of air move with about uniform velocity through the whole extent of the hot-air chamber. In my furnace the velocity is variable, the air passing most rapidly over those portions of the radiating surface with which it comes most closely in contact.

I will now particularly describe its construction and operation.

A is the shell or radiating surface. Within this shell is placed a fire-chamber of any approved construction, and furnished with suitable doors, through which fuel, &c., may be introduced, and the ashes, &c., be extracted.

The shell A is cast with corrugations, arranged so as to be transverse to the direction of the moving currents of air. These corrugations perform several functions: First, they interrupt, deflect, and cause to intermingle, the moving currents; second, they increase the extent of the radiating surface; and, third, they permit expansion and contraction to take place with more uniformity of effect than could be the case if they were differently arranged.

If the corrugations are placed vertically, as has hitherto been the practice, so as to be parallel with the direction of the moving currents, they form so many grooves or channels, along which currents of air are induced to run; and, while they increase the surface of radiation to some degree, they do not proportionately increase the power of the apparatus in imparting heat to a volume of air, because the presence of the corrugations is favorable to a rapid transit, but not to a thorough mixing of the hot and cold portions of the enclosed air.

When the corrugations are placed transversely to the moving currents, a rapid flow through the hot chamber is prevented, and the hot air is being constantly deflected and thrown off into the midst of that which is less heated.

The shell A is surrounded at a little distance by a wall, B, of brick or other material. This wall forms the outer jacket or case, and the enclosed space is the hot-air chamber. The deflecting-plates C C are secured to the inner sides of this wall B, and, projecting upward and inward, reach to within a short distance, say one inch, of the radiating surface A. The edges of these deflectors may be arranged so as to be opposite the highest points on the shell A, though this is not considered as being material. Above the top of the shell A, I make a chamber or reservoir, by extending the side walls upward as high as desired, and I insert my outlet-pipes D in the sides of this chamber whenever convenient to do so, for the reason that it is usually cheaper so to insert them, and for the further reason that they are then less likely to influence each other while in operation.

The upper set of deflecting-plates, C, act as partitions to divide the hot chamber or reservoir above from the heating-chamber below, and they compel the currents of air to enter said chamber or reservoir at the centre remote from the orifices of the outlet-pipes.

If the whole space between the radiating surface A and the wall B nowhere exceeded in thickness the distance between the edge of the plate C and said surface A, the friction of contact would be so great that a comparatively small volume of air would pass through that chamber; but when the general size of that chamber is ample, and narrow spaces only occur occasionally, the air will flow through those narrow spaces with great rapidity, and will move more slowly through the larger spaces between said deflecting-plates, and the effect will be a rapid flow in close contact with the heated material of the shell A, so rapid that the air will be warmed without being deprived of its moisture.

By using the deflecting-plates, the formation of separate currents of cool and hot air is completely prevented, the repeated passage through the narrow spaces between deflecting-plates and the radiating surface effectually mixing and commingling the air at a uniform temperature.

The advantages arising from the use of the deflectors C C do not depend upon the corrugated form of the shell, nor upon the presence of an air-chamber above the shell A, nor is the placing of the exit-pipes at the side material thereto, though I prefer so to place them, because less costly and more convenient.

In furnaces of large size, I insert one or more flues, E E, opening to the external air at the front of the furnace, (either directly into the apartment or cold-air duct,) and opening at the opposite end into the hot-air space behind the furnace. These flues I construct with corrugated walls, e e, converging and meeting at the top, the corrugations being vertical, so as to be transverse to the direction of the moving currents of air; and, in order to increase the surface of radiation, and to deflect and cause the volume of air passing through said flues to become thoroughly mingled, I insert the open-based cones, f f, at intervals through the length of the flue, as shown in the figures. The flues E E pass through the fire-chamber within the shell A, and the heated products of combustion have access to all sides of them.

The direct-draught flue F is provided to facilitate the kindling of a fresh fire, and the diving-flues G G to increase the distance to be traversed by the products of combustion before they escape from the furnace into the chimney-flue.

Claims.

1. The shell A, corrugated horizontally, as described, in combination with the deflecting-plates C C, substantially as and for the purpose set forth.
2. The flues E, constructed with corrugated walls e, and hollow cones f, substantially as and for the purpose set forth.
3. The deflecting-plates C C, or their equivalents, to deflect the upward currents of air against the radiating surfaces of the furnace.

SIDNEY SMITH.
